Patented Feb. 8, 1916.

UNITED STATES PATENT OFFICE.

NOLAN BAILEY HARMON, JR., OF GULFPORT, MISSISSIPPI.

TOY GUN.

1,171,197.

Specification of Letters Patent.

Patented Feb. 8, 1916.

Application filed September 1, 1915. Serial No. 48,404.

To all whom it may concern:

Be it known that I, NOLAN B. HARMON, Jr., a citizen of the United States, and a resident of Gulfport, in the county of Harrison and State of Mississippi, have invented 5 certain new and useful Improvements in Toy Guns, of which the following is a specification.

My invention is an improvement in toy 10 guns, and the invention has for its object to provide a gun of the repeating type, wherein the gun is provided with a magazine for containing pellets or projectiles, which are designed to be ejected from the gun by means 15 of compressed air, which is compressed between the pellets in the barrel of the gun by a plunger or rammer, and wherein the magazine is arranged to feed to the gun barrel adjacent to the breech, and in position in 20 front of the plunger or rammer, when the said plunger or rammer is withdrawn, and wherein means is provided for permitting the magazine to be filled, and for limiting the withdrawal of the plunger or rammer, 25 to prevent the entire removal of the same.

Furthermore, it is the object of this invention to provide a construction which shall increase the effectiveness of the above mentioned gun by: first, introducing in a quick 30 and expeditious manner a successive supply of pellets to the barrel in such a manner that each shall fit the barrel in an immediate and air-tight way; second, the holding of the about-to-be-ejected pellet within the barrel 35 (at or near the end) until an extraordinarily high air pressure has been reached, thus ejecting the pellet with loud report and force; and further to obtain a simple and inexpensive construction.

40 In the drawings: Figure 1 is a perspective view of the improved gun; Fig. 2 is a section on the line 2—2 of Fig. 1, showing the parts in one position; Fig. 3 is a similar view, showing the parts in another position; 45 Fig. 4 is an enlarged detail view of the muzzle of the gun; Fig. 5 is a section on the line 5—5 of Fig. 4; Fig. 6 is an enlarged section at the muzzle end of the gun, and Fig. 7 is a similar view at the breech end.

50 The present embodiment of the invention comprises a casing of oblong cross section, and having two bores, said casing consisting of the barrel 1, and the magazine 2. The bore 3 of the barrel extends entirely through

the same, while the bore 4 of the magazine 55 extends from near the muzzle of the barrel to near the breech, opening at the breech by a port or passage 5 into the barrel. The opposite end of the magazine is open, and is normally closed by a plug 6 in the form 60 of a cork or the like, and the barrel is provided with an enlarged conical recess 7, just below the passage 5, for receiving a pellet or projectile 8. This enlarged portion of the barrel is of the same diameter approximately 65 as a cross section of the magazine, and while the pellet has some play while in said recess, yet there is not enough room for another pellet to fall. This recess 7 tapers forward 70 into the barrel in such a way that when the pellet is driven out of the recess into the barrel it compresses and shapes the pellet to fit the barrel air-tight.

The pellets or projectiles are placed in the magazine through the open end, the cork 6 75 being removed for that purpose, and they pass rearwardly in the magazine to the passage 5, dropping into the barrel and seating in the recess 7, which prevents them from rolling either way of their own volition. 80

It will be noted from an inspection of Fig. 7, that at the recess 7 the barrel is enlarged slightly, as indicated at 17, that is, the recess 7 tapers forward as above mentioned in the barrel. A plunger or rammer 9 is arranged within the barrel for sliding movement, and the said plunger or rammer has a handle 10 at the end adjacent to the breech. This rammer is rounded to fit the barrel, and the annular shoulder 11 at the inner 90 end of the handle 10 forms a stop or abutment for engaging the adjacent end of the barrel, to limit the inward movement of the plunger or rammer.

The inner end of the plunger or rammer 95 is recessed or rounded, as shown at 12, to fit the periphery of a projectile 8, and a flexible member 13, as for instance a cord, is provided for connecting the plunger to the barrel. One end of the cord is secured to the 100 barrel at the breech, and on the under side of the barrel, by means of a tack 14 or the like, and the other end is secured to the handle on the under side and at the inner end thereof, by means of a tack 15 or the like. 105

The plunger or rammer is of a length to extend, when the shoulder 11 is in engagement with the adjacent end of the barrel, to

near the other end, as shown in Fig. 3, but the rammer does not extend the full length of the barrel when in the position of Fig. 3.

At a distance of one pellet diameter or thereabout in front of the point where the end of the plunger or rammer 12 comes to rest when it is driven fully into the barrel, and the shoulder 11 is in engagement with the adjacent end of the barrel, is a slightly contracted or "choked" part of the barrel 16 forming an interior projecting ring around the inner surface of the barrel at that point.

The cord or flexible member 13 is of a length to permit the plunger or rammer to be withdrawn to the position of Fig. 4, that is, to such position that the end 13 of the plunger or rammer will be at that side of the recess 7 and the passage 5 which is adjacent to the breech, and which is remote from the muzzle.

In operation, the magazine being filled with pellets, and with the rammer in the barrel, the pellets are restrained from dropping through the passage 5 into the barrel by the rammer, and they are held in the position of Figs. 2 and 3. To load the gun, the rammer is withdrawn into the position of Fig. 4. A pellet 8 now drops into the recess 7, and a forward movement of the plunger will drive the pellet through the tapering part of recess 7 into the barrel 3 in an airtight manner, and finally deposit the pellet at the position of Figs. 3 and 4 near the muzzle. Another withdrawal of the rammer to the position of Fig. 4 will permit a second pellet or projectile to drop into the barrel, seating in the recess 7, and now a forward movement of the plunger will compress the air between the pellet at the muzzle and that at the breech, and when this air is sufficiently compressed, the pellet at the muzzle will be driven forcibly from the barrel, causing an explosion or detonation as the pellet leaves the barrel.

The contracted part of the barrel 16 holds the pellet where it was originally deposited by the plunger until an extraordinarily high air pressure is reached between the pellets, when it is forced through contracted part of barrel 16 with great strength and noise. The second pellet which is driven forward by plunger, will take the place of the first pellet, forming an abutment against which the air is compressed.

After the first loading of the barrel, at every complete reciprocation of the rammer, a pellet will be discharged from the muzzle. The bore 4 of the magazine is of such size that while the pellets may move freely through the same, they cannot become jammed, and the same is true of the passage 5.

The barrel is of such size that some force is required to move the pellets, in order that there will be sufficient air compression be-

fore they are discharged. The flexible member 13 prevents the entire withdrawal of the plunger or rammer, limiting the withdrawal movement of Fig. 4, that is, with the inner end of the barrel, at the recess 7, and in position to permit a projectile to drop into the recess. When the magazine is empty, or nearly empty, the plug 6 is removed and a new store of pellets is inserted.

I claim:

1. A gun of the character specified, comprising a body consisting of a barrel and a magazine, the barrel and the magazine opening at one end of the body, and the barrel opening at the other end and communicating with the magazine by a passage, said magazine being above the barrel, a plunger or rammer mounted to slide in the barrel and having a handle, and having a shoulder between the handle and the plunger or rammer for limiting the inward movement of the plunger or rammer, said barrel having a recess at the communicating passage, and the inner end of the plunger being recessed to fit a projectile, said recess being adapted to receive a projectile, means for limiting the outward movement of the plunger to a position with the inner end thereof on the opposite side of the communicating passage from the muzzle, and a closure for the open end of the magazine.

2. A gun of the character specified, comprising a barrel open at both ends, and a magazine extending parallel with the barrel, and communicating by a passage with the barrel at the end adjacent to the breech, said barrel being contracted or choked at the passage and between the same and the muzzle of the barrel, a plunger or rammer mounted to slide in the barrel, means for limiting the withdrawal of the plunger or rammer to a point where the inner end is at the side of the passage remote from the muzzle, and a closure for the magazine.

3. A gun of the character specified, comprising a barrel, a plunger mounted to reciprocate in the barrel, and a magazine above the barrel and communicating with the bore of the barrel, at the end adjacent to the breech, for permitting a projectile to drop into the barrel in front of the plunger or rammer, said barrel having a recess at the passage for receiving a projectile and holding it in front of the plunger or rammer, the barrel being choked at the recess and between the same and the muzzle.

4. A gun of the character specified, comprising a barrel, a plunger mounted to reciprocate in the barrel, and a magazine above the barrel and communicating with the bore of the barrel at the end adjacent to the breech, for permitting a projectile to drop into the barrel in front of the plunger or rammer, the barrel being choked at the recess and between the same and the muzzle.

5. A gun of the character specified, comprising a barrel, a plunger mounted to reciprocate in the barrel, and a magazine above the barrel and communicating with the bore of the barrel, at the end adjacent to the breech, for permitting a projectile to drop into the barrel in front of the plunger or rammer, said barrel having a forward pointing, conically shaped recess under the passage for receiving, holding and with plunger compressing and shaping projectile as described.

6. A gun of the character specified, comprising a barrel, a plunger mounted to reciprocate in the barrel, and a magazine above the barrel and communicating with the bore of the barrel, at the end adjacent to the breech, for permitting a projectile to drop into the barrel in front of the plunger or rammer, said barrel having a forward pointing conically shaped recess at the passage capable of receiving, holding and with plunger compressing such projectile, a slightly contracted part of the barrel at or in advance of the point in the barrel where the plunger reaches when driven fullest in,

said contracted or "choked" part of the barrel capable of retarding exit of pellet substantially as described.

7. A gun of the character specified, comprising a barrel, a plunger mounted to reciprocate in the barrel, a magazine communicating with the bore of the barrel at the end adjacent to the breech for permitting a projectile to drop into the barrel in front of the plunger, said barrel being choked near the muzzle to temporarily hold a projectile to assist in compressing the air when a second projectile is moved toward the muzzle.

8. A gun of the character specified, comprising a barrel, a plunger mounted for sliding movement on the barrel, means for feeding pellets in succession to the barrel at the end adjacent to the breech, and an internal reduction in the barrel at the opposite end for temporarily holding a pellet to provide for air compression when the plunger moves toward the muzzle.
